ATTORNEY

UNITED STATES PATENT OFFICE

NORMAN FULLER HINTON, OF TIMPERLEY, ENGLAND, ASSIGNOR TO ASSOCIATED
ELECTRICAL INDUSTRIES LIMITED, A BRITISH COMPANY

ELECTRON-DISCHARGE DEVICE

Application filed November 21, 1928, Serial No. 70,548, and in Great Britain December 5, 1924.

My invention relates to the mounting of various electron discharge tube supports and it has particular reference to the mounting of thermionic valves such as are used in wireless telegraphy and telephony.

An object of the invention is to provide improved means for protecting devices of this nature from extraneous vibration.

Another object of my invention is to prevent the tube elements from giving rise to microphonic noises.

Another object of my invention is to provide an easily assembled tube socket which, at the same time, will be durable and not easily broken while in use.

Still another object of my invention is to provide a socket which will, at all times, insure good electrical contact between the tube terminals and the holding means.

20 In the preferred form of my invention, I construct a tube socket having a portion adapted to make a mechanical connection to a panel or other holding means, and having between that portion and the tube holding 25 portion a spiral spring or other resilient means.

The invention preferably comprises a holder or socket having two members connected at least by one axial or longitudinal spring, 30 one of these parts being adapted to be mounted on the panel or supported, while the other is adapted to carry the electron discharge device. To prevent undesired separation of these two parts, I provide a stop or an abutment, and the spring members may be utilized as current conductors to and from the electron discharge device.

For a complete understanding of my invention, reference is made to the drawing accompanying and forming a part of this application, in which

Figure 1 shows a plan view of a preferred form of my invention, and

Fig. 2 is a view, in section, on the line A—B of Fig. 1.

The main, or base portion 1 of my device, as illustrated in Figure 2, is preferably of ebonite, porcelain, a phenolic-condensation product or other good insulating material and is provided with a plurality of apertures

2. Mounted in each aperture and securely held in place such as by molding is a conducting pin 3, which is provided with threads, as shown, but which may be plain, or split so as to be frictionably held in the usual type 55 of socket.

That portion 4 of each pin 3 which is secured to the base portion 1 is formed with an opening 5, threaded to receive a screw 6, which in turn serves to hold the lower end 60 of coiled spring 7 against, and in electrical contact with the head of a pin 3. This spring 7 may be welded to the screw 6, or otherwise united thereto or clamped thereby, or it may be soldered to a washer 8 which is in turn 65 held down by the screw 6, and preferably has a diameter less than that of the aperture 2 for reasons which will later appear.

The base portion 1 also has formed there-in a central opening in which is inserted a 70 rod, or pin 9, which may or may not be of insulating material. Removably carried by this rod 9, is an abutment, or stop 10, held in place by a screw 11. The functions of the rod and abutment will be later described. 75

A floating, or resilient tube-receiving portion of my socket is shown generally at 12, and is in the form of a disc of insulating material provided with a plurality of openings 13, and a large central opening 14. Each of 80 the openings 13 is provided with a co-axial bushing 15, made of conducting material, molded in, or otherwise secured to the disc 12. The upper end of each spring 7 is soldered or otherwise secured to one of the bushings 15, this completing a conductive path from each pin 3 to its corresponding bushing. The central rod 9 passes through the opening 14, which is made of such size that the edges thereof do not come in contact with the pin. The abutment 10 is, however, larger in diameter than opening 14, which prevents undue elongation of springs 7 when it is desired to remove a tube. 85

It will be seen that, when a tube is inserted in the upper disc 12, the pins of the tube make electrical contact with the rings 15 which are conductively connected with the pins 3. On pressing the tube into the socket, the upper disc gives to a slight extent, 90 100

the travel downward being limited by its abutting against the lower section 1. On removal of the tube the abutment 10 comes into play and permits the tube to be withdrawn without difficulty.

5 By reason of the fact that the disc 12 is out of actual contact with any portion of the apparatus except through the springs 7, it is obvious that vibrations can reach the tube 10 only through these springs, in which case they are absorbed or damped out. The aperture 14 is made of such size that, at no time while in use, does the disc 12 come into contact with the column 9, the weight of the 15 tube being sufficient to keep the springs 7 slightly compressed and the disc 12 out of contact with the abutment 10.

The tube, therefore when inserted in the upper disc 12, has a limited vertical movement, as well as a limited horizontal movement, and it is at all times supported resiliently.

20 My improved socket, therefore differs in many essential respects from resilient sockets 25 heretofore provided. It may be used either for mounting directly on a panel or sub-panel, or it may be used as an auxiliary holder in connection with conventional sockets. It is 30 comparatively cheap to manufacture, is easily assembled, and is rugged and durable.

35 A further advantage of my invention lies in the fact that the tube is, at all time, resiliently supported, yet is not permitted to depart appreciably from its fixed position in a set, either vertically or horizontally, which 40 obviates much of the danger of the tube being broken while in use.

Although I have described but a single 45 specific form of my invention, various modifications may be made therein without departing from the spirit and scope thereof, as indicated in the appended claims.

I claim as my invention:

46 1. In a combination with an electron tube having a base carrying contact pins, and a socket having receptacles adapted to receive said pins, an adapter comprising a plate having a pin arrangement like that of said base, a second plate having a receptacle arrangement like that of said socket, means to maintain said last named pins and receptacles in substantial alignment, and flexible means connecting each pin of said plate with the receptacle of said other plate aligned therewith.

50 2. In combination with an electron tube having a base carrying contact pins and a socket having receptacles adapted to receive said pins, an adapter comprising a plate having a pin arrangement like that of said base, a second plate having a receptacle arrangement like that of said socket, means to maintain said last named pins and receptacles in substantial alignment, means to limit the relative movement of said plates and flexible

means connecting each pin of said plate with the receptacle of said other plate aligned therewith.

I testify whereof, I have hereunto subscribed my name this 29th day of October, 1925.

NORMAN PULLEN HINTON.
